UNITED STATES PATENT OFFICE.

HENRY A. HISGEN, THOMAS WOLFE, TOM ARMITAGE, JR., AND GEORGE C. HISGEN, OF ALBANY, NEW YORK, ASSIGNEES TO HISGEN BROTHERS, OF ALBANY, NEW YORK.

METAL CONTAINER OR BOX.

1,193,461.

Specification of Letters Patent. Patented Aug. 1, 1916.

Application filed June 3, 1915. Serial No. 31,822.

To all whom it may concern:

Be it known that we, HENRY A. HISGEN, THOMAS WOLFE, TOM ARMITAGE, JR., and GEORGE C. HISGEN, citizens of the United States, residing at Albany, in the county of Albany and State of New York, have invented certain new and useful Improvements in Metal Containers or Boxes; and we do hereby declare the following to be a full, clear, and exact description of the invention, such as will enable others skilled in the art to which it appertains to make and use the same.

Our invention relates to new and useful improvements in metal containers or boxes, and more particularly to that class adapted to be used for containing salves, polishes and similar substances, and our prime object is to provide a cover for the body of the container or box having portions thereof constructed in such manner as to create a frictional seal between the top and body of the container.

A further object is to provide a suitable reinforcing section for the body of the container. And a further object is to provide rolls at the selvage edges of the body and cover respectively.

Other objects and advantages will be hereinafter set forth and more particularly pointed out in the accompanying specification.

In the accompanying drawings which are made a part of this application, Figure 1 is a top plan view of the container or box. Fig. 2 is an edge elevation thereof, and Fig. 3 is an enlarged detail sectional view through a portion of the container, showing the cover in position to be forced into engagement with the upper edge of the body of the container.

Referring to the drawings in which similar reference numerals designate corresponding parts throughout the several views, 1 indicates the body of the container which is preferably stamped from a sheet of metal and comprises the bottom and side walls 2 and 3 respectively, the side wall 3 having a circumferential reinforcing rib 4 formed by bending outwardly a portion of the side wall 50 and crimping the same together until the parallel sections thereof rest in a horizontal position. The edge portion 5 of the side wall 3 above the rib 4 is preferably slightly tapered inwardly from the rib to

its upper edge, the extreme upper edge of 55 the edge portion being bent into a roll 6 so that the upper edge will present an absolutely smooth surface. Cooperating with the body 1 is a cover or lid 7, the depending wall 8 of which is provided with an offset or 60 flared portion 9 between its lower edge and its point of connection with the cover proper, said offset portion being directed at such an angle as to frictionally engage the outer face of the edge 5 of the body with sufficient 65 force to securely hold the cover over the body and also form a substantially watertight seal when the roll 6 comes in contact with the straight edge of the wall 8 above the flared portion 9. 70

The inclination of the offset portion 9 is slightly greater than the inclination of the edge 5 so that in securing the cover over the body of the container it is necessary to apply force in directing the cover over the box, the 75 frictional engagement of the offset portion causing the cover to firmly adhere to the edge 5, the downward movement of the cover being limited by the straight edge of the wall 8, above the flared portion 9, coming in 80 contact with the roll 6 so that a space is left between the rib 4 and the rolled edge 10 of the cover when the cover is fully seated on the container, into which any suitable instrument may be introduced for removing the 85 cover. It will likewise be seen that by providing the roll 10 at the selvage edge of the cover, an absolutely smooth surface at the edge will be provided, and if desired, reinforcing rings 11 and 12 may be introduced 90 into the rolls 6 and 10 respectively, although, in most instances they will be omitted from the structure.

This form of container can be very cheaply constructed and at the same time 95 rendered extremely strong and durable in view of the rolled edges of the two sections and the provision of the reinforcing rib. And it will likewise be seen that by placing the angle or inclination of the edge 5 of the 100 body 1 at a different degree from the angle of the offset portion 9, the two parts of the container will be securely held together by frictional contact and a perfect seal formed between the two sections. And it will likewise be seen that the cover can be readily removed from the body of the container, in view of the fact that any suitable instru- 105

ment may be introduced between the rib and the roll 10 of the cover to apply prying pressure thereagainst.

Having thus fully described our invention what we claim as new and desire to secure by Letters Patent of the United States is:—

1. A metallic container comprising a body having an upstanding side wall, a circumferential rib formed by swaging out portions of said wall and crimping the parts thereof until the sections are parallel and in horizontal position, that portion of the wall above the rib being inclined inwardly, the upper edge of said wall being formed into an inwardly curved roll, a cover having a depending wall, said wall comprising two straight portions and an outwardly and downwardly flared portion between said straight portions, the diameter of the lower straight portion being greater than the diameter of the upper straight portion, said flared portion being adapted to frictionally engage the inclined portion of the wall of the body, the lower free edge of the cover wall being formed into an outwardly curved roll, the upper edge of the straight portion of the cover wall at its intersection with the flared portion forming a stop for the downward movement of the cover when engaged with the roll of the body wall.
2. A metallic container comprising a body portion, the upstanding wall of which is

provided with a peripheral rib between its upper and lower edges, the walls of the rib being crimped into close proximity to each other and resting in a horizontal position, a cover for the body, the depending wall of which is provided with an upper and lower straight portion of different diameters and an outwardly flared portion connecting said upper and lower straight portions, said flared portion being adapted to frictionally engage that portion of the wall of the body above the rib and hold the cover in position over the body, the edge of the upper straight portion of the depending wall at the point of its connection with the flared portion engaging the free edge of the wall of the body whereby the descent of the cover onto the wall of the body portion will be stopped and the lower edge of the lower straight portion held slightly spaced from said rib whereby an instrument may be introduced between said edge and rib to remove the cover.

In testimony whereof we have signed our names to this specification in the presence of two subscribing witnesses.

HENRY A. HISGEN.
THOMAS WOLFE.
TOM ARMITAGE, JR.
GEORGE C. HISGEN.
